UNITED STATES PATENT OFFICE

152,314

DESIGN FOR A BALL GAME BOARD

George Ray Armstrong, McKeesport, Pa.

Application November 1, 1946, Serial No. 134,461

Term of patent 14 years

(Cl. D34—5)

To all whom it may concern:

Be it known that I, George Ray Armstrong, a citizen of the United States of America, residing at McKeesport, in the county of Allegheny and State of Pennsylvania, have invented a new, original, and ornamental Design for a Ball Game Board, of which the following is a specification, reference being had to the accompanying drawing, forming a part thereof, wherein:

I claim:

The ornamental design for a ball game board, as shown.

G. RAY ARMSTRONG.
